H. J. BRAGDON

STOPPER FOR BOTTLES AND THE LIKE

Filed Oct. 4, 1919

Fig. 1

INVENTOR

HERBERT J. BRAGDON,
by Ralph Koenig, ATTORNEY.

UNITED STATES PATENT OFFICE.

HERBERT J. BRAGDON, OF ALTON, ILLINOIS, ASSIGNOR TO THE CHICAGO STOPPER COMPANY, OF CHICAGO, ILLINOIS, A CORPORATION OF ILLINOIS.

STOPPER FOR BOTTLES AND THE LIKE.

Application filed October 4, 1919. Serial No. 328,407.

To all whom it may concern:

Be it known that I, HERBERT J. BRAGDON, a citizen of the United States, residing at Alton, county of Madison, State of Illinois, have invented a certain new and useful Improvement in Stoppers for Bottles and the like, of which the following is a specification, reference being had to the accompanying drawing, forming a part thereof.

10 This invention relates to a certain new and useful improvement in stoppers for bottles and other containers, the chief object of my present invention being to provide or construct an efficient stopper adapted for repeated use, which may be readily inserted or fitted into the neck of a bottle, which, when inserted or fitted into the neck of a bottle, will be automatically effectively held in fluid-tight engagement with the bottle, and which may be conveniently removed from the bottle without the aid or use of a cork-screw or other such implement or tool.

With the above and other objects in view, my present invention resides in the provision of an efficient stopper adapted for repeated use including in its construction a body comprising a strip of suitable material coiled, wound or spooled upon itself and constructed with the outer layer of its spooled strip preferably fixed from unwinding and the inner layers of its spooled strip relatively loose.

The stopper so constructed is adapted to be forced into the mouth of a bottle or other container so that the body of the stopper will be compressed by the container wall. The stopper thus compressed within the container will form a fluid tight closure, and actual experiments have demonstrated that the stopper will withstand very considerable gaseous pressures within the container. Nevertheless, the stopper may be readily removed from the container when desired by a rotative movement of the head of the stopper. Such rotative movement more tightly winds the coiled material forming the body of the stopper, this being made possible by the fact that at its periphery the body of the stopper is frictionally retained by the wall of the container, while the inner convolutions of the coil are loosely enough wound to permit of further coiling. It is obviously true that

the coil will be frictionally retained at its periphery by the container wall to permit this further winding, whether the outer convolutions of the coil be free or whether they be fixed from unwinding by adhesive or by a closure cap, as is preferably the case in order to permit repeated use of the stopper. By rotative movement of the head and consequent tighter coiling of the body of the stopper, the pressure against the container wall is relieved and the stopper is readily removable. On removal of the stopper, the body tends automatically again to assume its normal size and contour.

In the accompanying drawing,

Figure 1 is a plan view of a strip of material adapted to be wound or spooled upon itself to form the body of the stopper;

Figure 2 is a plan view of a section of thin spring material adapted to be wound or spooled with the body-strip to form or provide auxiliary tensioning or expanding means for the stopper;

Figure 3 is an elevational view of the core or winding-post of the stopper;

Figure 4 is an enlarged plan view of the core or winding-post;

Figure 5 is a perspective view of a cap having engagement in the finished stopper with the core or winding-post for facilitating axial turning or winding of the core or post;

Figure 6 is a perspective view of a closure-cap for the inner end of the stopper;

Figure 7 is a plan view of the core or winding-post with the body-strip and auxiliary spring-strip held or engaged therein preparatory to formation of the finished stopper, showing by an arrow the direction of winding of the strips to form the finished stopper;

Figure 8 is an enlarged vertical sectional view of the finished or complete stopper;

Figure 9 is an elevational view of the stopper operatively disposed in a bottle-neck shown in vertical section;

Figure 10 is an elevational view of the stopper with a slightly modified form of closure-cap;

Figure 11 is a view, partly in elevation and partly in vertical section, of a slightly modified form of stopper adapted especially for bottles the necks of which are formed with an internal shoulder;

Figure 12 is also a view, partly in elevation and partly in vertical section, of another slightly modified form of stopper;

Figure 13 is a view in elevation of a conical or tapered stopper embodying my invention in slightly modified form;

Figure 14 is a plan view of the strip used in forming the body of the stopper illustrated in Figure 13;

Figure 15 is a vertical sectional view of still another modified form of stopper embodying my invention; and

Figure 16 is a fragmental plan view of the strip used in forming the body of the stopper illustrated in Figure 15.

Referring to the said drawing, in which like reference characters refer to like parts throughout the several views, and more especially now to the preferred form of stopper illustrated in Figures 1 to 9, both inclusive, 1 indicates a substantially cylindrical core or post constructed preferably of sheet metal, slotted longitudinally, as at 2, from its upper end to closely adjacent its lower end, and provided at its upper end with prongs 3—3, for purposes shortly appearing.

4 indicates a strip of suitable material, such as, for instance, manilla paper, of preferably some stiffness, but possessing preferably inherently some resilient flexibility. The strip 4 is of suitable length depending upon the desired circumferential size of the finished stopper and preferably is of rectangular-oblong shape, the strip 4, when wound or spooled, as hereinafter appearing, forming or providing what I may term or designate the body of the stopper.

5 indicates a substantially rectangular-oblong shaped section of thin spring metal, such as, for instance, steel. This strip 5 is preferably of somewhat less width and considerably shorter in length than the main strip 4, as seen especially by reference to Figures 1, 2, and 7.

In the formation of the stopper, the strips 4 and 5, disposed in flatwise relation, are inserted through the slot 2 of the post 1, post 1 being disposed substantially midway the length of the strips, as seen in Figure 7; and in this connection it will be noted in Figure 1 that the main strip 4 is provided approximately centrally and at its lower end with a cut-out 6 adapted to accommodate the lower, non-slotted end of the post 1. The post 1 is then axially rotated counter-clockwise, or in the direction of the arrow, Figure 7, and the strip 4, together with the, and afterwards concealed, strip 5, coiled, wound or spooled more or less to-tightly thereabouts, a space in the winding preferably immediately adjacent the core or post, as shown, being provided to permit of some compression of the stopper on insertion into a bottle and also to facilitate removal of the

stopper as more fully hereinafter appears. As seen in Figure 8, the lower end of post 1 is preferably in about the same plane as the lower margin of the strip 4, which result is incident to the cut-out 6. After the strips 4 and 5 have been so wound or spooled about the core or post 1, and in order to obviate or prevent axial leakage through the stopper, I fix over the lower end of the spooled strip 4 and the post 1 a closure-cap 7, which is constructed of any suitable preferably flexible material, such as relatively thin rubber-lined paper pressed into cup-shape. By preference, securing of the cap 7 is effected by a dab or two of suitable glue or cement applied at a point or two on the inner peripheral or flanged surface of the cap for adhesion to the outer peripheral face of the spooled strip 4. The spooled strip 4 and its closure-cap 7 are now preferably suitably coated with paraffin, which increases the durability of the stopper, renders the stopper substantially water and moisture proof, and at the same time firmly fixes or holds the outer ends of the strip 4 from unwinding and also additionally secures the closure-cap upon the spooled strip. It may be here stated that, while the body-strip 4 is so fixed at its ends from unwinding, its inner layers are loose one from the other.

For facilitating the axial turning of the core or post 1 and also for finishing the upper end of the stopper, I employ a head 8 preferably constructed of relatively thin sheet metal, pressed into cup-shape, and provided in its top or end wall with a pair of suitable slots 9—9 for receiving and accommodating the prongs 3 of the post 1, which prongs 3, when fitted through the slots 9, are bent and clenched down upon the cap 8 and the cap 8 thereby firmly and rigidly held in encircling position upon and in connection with post 1 and the spooled or coiled body-strip 4, as seen in Figures 8 and 9. The head or upper cap 8, being so arranged to surround the upper end of the coiled or spooled strip 4, serves further, when the prongs 3 are clenched thereupon, as described, to hold the post 1 and strip 4 together and the outer ends of the strip 4 from unwinding.

Under the normal or inherent tendency of the strip 4 to unwind, aided in such tendency by the concealed spring or auxiliary tensioning strip 5, the inner layers or windings of the strip 4, as well as the layers or windings of the strip 5, being loose one from the other, the stopper will normally tend to assume a particular circumferential dimension or size, that is to say, a particular size adapted to fit a bottle having a neck of corresponding particular size, and as such or normally the stopper is adapted to be forced and compressed into a bottle neck. I have found from experience that the stop-

per, when so inserted and fitted in the neck of the bottle, will automatically effectively engage in fluid tight relation with the neck of the bottle, and will withstand very considerable pressure within the container. The stopper may be easily removed, however, by a slight rotation of the head which causes the core or post to wind the coil more tightly, while at its periphery the coil is retained by the friction between the container wall and the periphery of the body, whereby the compression of the stopper within the container wall is released and the stopper rendered readily removable. Preferably the outer peripheral or flanged surface of the head or upper cap 8 is knurled, as shown, so that, when grasped to extract the stopper, the head 8 may be readily turned axially to wind the coil more tightly and release the compression of the stopper within the container. When so removed from the bottle and turning pressure upon the head 8 is released, the stopper will automatically, under the normal or inherent unwinding tendency of the body-strip 4, aided in such tendency as before stated by the concealed spring strip 5, tend to assume its full normal size, for re-insertion into the bottle.

My new stopper may be inexpensively manufactured, has from experience been found most efficient in operation, and can be effectively used repeatedly.

In the repeated use of the preferred form of the stopper, just described, the lower cap often crimps or folds upon itself at one or more points along its peripheral or flanged portion. To obviate such folding or crimping, the lower cap 7^a may be provided with one or more axial cut-outs 10, as shown, the stopper illustrated in Figure 10 being otherwise identical in form and construction with the described preferred form of the stopper.

In Figure 11, I illustrate a modified form of the stopper, which is especially designed for use in connection with bottles having an internal shoulder. In this modified form of stopper, the lower-cap is dispensed with, and a closure-disk 11 preferably of watertight material, such as, for instance, cork, is employed, as shown, to close the lower end of the stopper-body, the disk 11 being securely held in operative position by a crimping thereupon, as at 12, of the lower marginal edge of a container-capsule 13 snugly fitted about the wound body-strip 4 with its upper marginal edge disposed beneath the peripheral or flanged portion of the head or upper cap 8.

In the modified form of the stopper illustrated in Fig. 12, an approximately rigid disk 14 centrally underlies the body-strip 4 and is secured or fixed to the post 1^a by means of a prong 15 projecting from the lower end of the post and clenched as shown upon the disk 14, the stopper being likewise

provided, as in the preferred form of the stopper, with a lower closure-cap 7^b. In this form of the stopper, which is otherwise than stated substantially identical in form and construction with the preferred form of the stopper, the disk 14 serves to re-enforce the stopper to withstand, without rupture, relatively hard outward pulls upon the stopper in attempting to remove the stopper from the neck of a bottle.

The modified tapering form of the stopper illustrated in Figure 13 has its body formed or constructed of a strip 4^a of arcuate shape, as shown in Figure 14, and is adapted especially for use with bottles or other containers whose necks have a decided taper, the construction of this form of the stopper being otherwise identical with the construction of the preferred form of the stopper.

In Figure 15 I illustrate a modified form of the stopper, in which the body is formed of a strip 4^b provided along its upper marginal edge with a ribbon 16 extending separately nearly, but not wholly, the length of the strip, the ribbon 16 being integral with the strip 4^b at its inner end, as seen in Figure 16. In the formation of this form of the stopper, the strip 4^b and the ribbon 16 are simultaneously wound or spooled in one direction only, in a manner substantially similar to the winding of an ordinary clock-spring, the body so formed being closed and the body-strip being held from unwinding at the lower end of the stopper by a closure-cap 7^c substantially similar to the closure-cap 7 and similarly fixed to the body of the stopper. Fitted upon the body of the stopper at, and to close, its upper end, is a head or cap 17 formed preferably of a single piece of suitable material, such as paper, to comprise a central circular projection 18, which is disposed within the wound or spooled ribbon and strip, as shown, to provide substantially a core for the stopper, and a marginal or peripheral flange 19 which surrounds the wound ribbon 16 and also the upper marginal portion of the strip 4^b, serving thereby to hold the ribbon 16 and the strip 4^b from unwinding.

The cap 17, further, is glued or otherwise suitably fixed at its flange 19 to the ribbon 16 and thus serves additionally as a winding member for the strip 4^b. Normally, as with the preferred form of the stopper, this modified form of the stopper is of a circumferential size to fit a particular size of bottle-neck and when fitted into the bottle-neck provides a most efficient stopper. To remove the stopper from the bottle-neck, a slight turning movement imparted to the head or cap 17 will, through the engagement of the head or cap 17 with the ribbon 16, which, as before stated, is integral at its inner end with the inner end of the strip 4^b, more tightly wind

the strip 4^b upon itself, the stopper being then readily and conveniently removable from the bottle without the use or aid of a cork-screw or other like tool, and the stopper 5 similarly, as in the preferred form of the stopper, then, on removal, again, under the inherent resilient flexibility of the strip 4^b, tending to assume and take its normal, fully expanded shape, size, and contour.

10 From the foregoing, it will be observed that stoppers embodying my invention may have various forms, each, however, being possessed of the same general construction and plan of operation, that is to say, a body 15 comprising a strip of suitable material so wound or spooled upon itself that the finished stopper is capable of being compressed within the mouth of a container and the coil thereafter being capable of being more 20 tightly wound, whereby the stopper is adapted not only to fit effectively and repeatedly, but also to be removed readily and conveniently, without the aid of a cork-screw or other like tool, from the neck of a bottle or 25 other container with which the stopper is being used; and it is to be understood that changes in the form, construction, arrangement, and combination of the several parts 30 of the stopper may be made and substituted for those herein shown and described without departing from the nature and principle of my invention. My invention may be used to great advantage for other purposes than merely for stoppers for bottles 35 and it should be so understood.

Having thus described my invention, what I claim and desire to secure by Letters Patent is:

1. As a new article of manufacture, a container-stopper including, in combination, a circumferentially contractible body comprising a strip of material wound upon itself to a normal circumferential dimension, the outer end of the strip being fixed from 40 unwinding and inner windings of the strip being loose one from the other, and means having connection with the strip for additionally winding the same to contractingly 45 reduce the normal circumferential dimension of the body.

2. As a new article of manufacture, a container-stopper including, in combination, a circumferentially contractible body comprising a strip of material wound upon itself to a normal circumferential dimension, the outer end of the strip being fixed from unwinding and inner windings of the strip 55 being loose one from the other, and means comprising a head-cap having connection with the strip for additionally winding the same to contractingly 60 reduce the normal circumferential dimension of the body.

3. As a new article of manufacture, a container-stopper including, in combination, a circumferentially contractible body comprising 65

70 a strip of material wound upon itself to a normal circumferential dimension, the outer end of the strip being fixed from unwinding and inner windings of the strip being loose one from the other, means comprising a head-cap having connection with the strip for additionally winding the same to contractingly 75 reduce the normal circumferential dimension of the body, and means having engagement with the body for providing a closure for the lower end thereof.

4. As a new article of manufacture, a container-stopper including a circumferentially contractible and expansible body comprising a strip of resiliently flexible material wound upon itself to a normal circumferential dimension, the outer end of the strip being fixed from unwinding, inner windings of the strip being loose one from the other, whereby the strip, after insertion 80 of the stopper in a container is adapted for additional winding to contractingly reduce the normal circumferential dimension of the body to facilitate removal of the stopper from the container, the body on expansion 85 tending automatically to assume its normal circumferential dimension.

5. As a new article of manufacture, a container-stopper including a circumferentially contractible and expansible body comprising a strip of resiliently flexible material wound upon itself to a normal circumferential dimension, the outer end of the strip being fixed from unwinding and inner windings of the strip being loose one 90 from the other, and axially rotatable means having engagement with the strip for additionally winding the same to contractingly reduce the normal circumferential dimension of the body, the body on expansion 95 tending automatically to assume its normal circumferential dimension.

100 6. As a new article of manufacture, a container-stopper including, in combination, a circumferentially contractible and expansible body comprising inner and outer strips of different material wound together upon themselves to a normal circumferential dimension, the outer end of the outer strip being fixed from unwinding and inner windings of both strips being loose, and axially 105 rotatable means having connection with both strips for additionally winding the same to contractingly reduce the normal circumferential dimension of the body, the body on expansion 110 tending automatically to assume its normal circumferential dimension.

115 7. As a new article of manufacture, a container-stopper including, in combination, a circumferentially contractible and expansible body comprising an outer strip of paper and an inner strip of thin sheet metal wound together upon themselves to a normal circumferential dimension, the outer 120

- end of the paper strip being fixed from unwinding and inner windings of both strips being loose, and axially rotatable means for additionally winding the strips to contractingly reduce the normal circumferential dimension of the body, said means including a core disposed within and having engagement with both wound strips, and a head-cap disposed upon the body and having engagement with the core, the body on expansion tending automatically to assume its normal circumferential dimension. 8. As a new article of manufacture, a container-stopper including, in combination, a circumferentially contractible and expansible body comprising an outer strip of paper and inner strip of thin sheet metal wound together upon themselves to a normal circumferential dimension, the outer end of the paper strip being fixed from unwinding and inner windings of both strips being loose, means disposed upon the body for providing a closure for the lower end thereof, and axially rotatable means for additionally winding the strips to contractingly reduce the normal circumferential dimension of the body, said last-named means comprising a core disposed within and having engagement with both wound strips, and a flanged head-cap disposed upon and surrounding the upper end of the body and having engagement with the core, the body on expansion tending automatically to assume its normal circumferential dimension. 9. A container stopper comprising a coiled strip of material compressible by the container wall and adapted to be frictionally retained at its periphery by the container wall, and said strip being adapted to be coiled more tightly to relieve the pressure thereof against the container wall. 10. A container stopper comprising a coiled strip of material compressible by the container wall and adapted to be frictionally retained at its periphery by the container wall, and a member connected with the strip and adapted, on rotation, to coil the strip more tightly to relieve the pressure thereof against the container wall. 11. A container stopper comprising a coiled strip of material compressible by the container wall and adapted to be frictionally retained at its periphery by the container wall, and a rotative head fixedly connected with the strip and overlaying the top of the coil, said head being adapted, on rotation, to coil the strip more tightly to relieve the pressure thereof against the container wall. 12. A container stopper comprising a body including a coiled strip of material and material enclosing the bottom and periphery of the coil, said body being compressible by the container wall and the coil being adapted to be frictionally retained at its periphery by the container wall, and a member engaging the strips intermediate their ends, and a head fixed to said member and adapted, on rotation, to coil the strips more tightly to relieve the pressure thereof against the container wall. 13. A container stopper comprising a strip of material and a second strip of resilient material coiled together and compressible by the container wall, the coil being adapted to be frictionally retained at its periphery by the container wall, and said strips being adapted to be coiled more tightly to relieve the pressure thereof against the container wall. 14. A container stopper comprising a strip of material and a second strip of resilient material coiled together and compressible by the container wall, the coil being adapted to be frictionally retained at its periphery by the container wall, and a member connected with the strips and adapted on rotation, to coil the strips more tightly to relieve the pressure thereof against the container wall. 15. A container stopper comprising a strip of material and a second strip of resilient material coiled together and compressible by the container wall, the coil being adapted to be frictionally retained at its periphery by the container wall, and a rotative head fixedly connected with the strips and overlaying the top of the coil, said head being adapted, on rotation, to coil the strips more tightly to relieve the pressure thereof against the container wall. 16. A container stopper comprising a body including a strip of material and a second strip of resilient material coiled together and material enclosing the bottom and periphery of the coil, said body being compressible by the container wall and the coil being adapted to be frictionally retained at its periphery by the container wall, and a rotative head fixedly connected with the strips and overlaying the top of the body, said head being adapted, on rotation, to coil the strips more tightly to relieve the pressure of the body against the container wall. 17. A container stopper comprising a coiled strip of material compressible by the container wall and adapted to be frictionally retained at its periphery by the container wall, a member engaging the strip intermediate its ends, and a head fixed to said member and adapted, on rotation, to coil the strip more tightly to relieve the pressure thereof against the container wall. 18. A container stopper comprising a strip of material and a second strip of resilient material coiled together and compressible by the container wall, the coil being adapted to be frictionally retained at its periphery by the container wall, a member engaging the strips intermediate their ends, and a head fixed to said member and adapted, on rotation, to coil the strips more tightly to relieve the pressure thereof against the container wall.

and a head fixed to said member and adapted, on rotation, to coil the strips more tightly to relieve the pressure thereof against the container wall.

5 19. A container stopper having an axially inextensible body comprising a coiled strip of material, the body having a normal form adapting it to be forced into a container to effect a fluid-tight closure thereof, the strip 10 being adapted thereafter to be coiled more tightly, and a member engaging the strip adapted, on rotative movement, to coil the strip more tightly, whereby the body will be released from a container, and, on removal, will assume its normal form.

15 20. A container stopper having an axially inextensible body comprising a coiled strip of material, the body having a normal form adapting it to be forced into a container to 20 effect a fluid-tight closure thereof, the strip being adapted thereafter to be coiled more tightly, a shaft engaging the strip, and a head secured to the shaft and adapted, on 25 rotative movement, to coil the strip more tightly, whereby the body will be released from a container, and, on removal, will assume its normal form.

25 21. A container stopper having an axially inextensible body comprising a coiled strip 30 of material, the body having a normal form adapting it to be forced into a container to effect a fluid-tight closure thereof, the strip being adapted thereafter to be coiled more tightly, a shaft engaging the strip, and a 35 head secured to the shaft and closely overlying the top of the body and adapted, on rotative movement, to coil the strip more tightly, whereby the body will be released from a container, and, on removal, will assume its normal form.

40 22. A container stopper having an axially inextensible body comprising two strips of material coiled together, one of the strips being resilient material, the body having a 45 normal form adapting it to be forced into a container to effect a fluid-tight closure thereof, the strips being adapted thereafter to be coiled more tightly, a shaft engaging

the strips, and a head secured to the shaft and adapted, on rotative movement, to coil 50 the strips more tightly, whereby the body will be released from a container, and, on removal, will assume its normal form.

23. A container stopper having an axially inextensible body comprising two strips of 55 material coiled together, one of the strips being resilient material, and protective material enclosing the end and periphery of the coil, the body having a normal form adapting it to be forced into a container to 60 effect a fluid-tight closure thereof, the strips being adapted thereafter to be coiled more tightly, a shaft engaging the strips, and a head secured to the shaft and adapted, on 65 rotative movement, to coil the strips more tightly, whereby the body will be released from a container, and, on removal, will assume its normal form.

24. A container stopper having an axially inextensible body comprising two strips of 70 material coiled together, one of the strips being resilient material, the inner end and periphery of the body being covered with protective material, the body having a normal form adapting it to be forced into a 75 container to effect a fluid-tight closure thereof, the strips being adapted thereafter to be coiled more tightly, a shaft engaging the strips, and a head secured to the shaft and closely overlying the top of the body 80 and adapted, on rotative movement, to coil the strips more tightly, whereby the body will be released from a container, and, on removal, will assume its normal form.

25. A container stopper having an axially 85 inextensible body comprising a coiled strip of material, the body having a normal form adapting it to be forced into a container to effect a fluid-tight closure thereof, and a member engaging the strip adapted, on 90 rotative movement, to render the stopper removable from a container without axial distortion of the stopper.

In testimony whereof, I have signed my name to this specification.

HERBERT J. BRAGDON.
